Primary Examiner — Adir Aronovich*Assistant Examiner* — Ramzi Almatrahi(74) *Attorney, Agent, or Firm* — Berkeley Law & Technology Group LLP(57) **CLAIM**

The ornamental design for a lens cover for camera, as shown and described.

DESCRIPTION

FIG. 1 is a top, right, and front perspective view of a lens cover for camera showing my new design;

FIG. 2 is a front elevational view of FIG. 1;

FIG. 3 is a rear elevational view of FIG. 1;

FIG. 4 is a right side elevational view of FIG. 1;

FIG. 5 is a left side elevational view of FIG. 1;

FIG. 6 is a top plan view of the cover of FIG. 1;

FIG. 7 is a bottom plan view of the cover of FIG. 1; and,

FIG. 8 is a top, right, and front perspective view thereof, showing the lens cover sliding over the lens of a camera, with the camera depicted in broken lines as environmental subject matter which forms no part of the claimed design.

The broken lines depict portions of a lens cover for camera in which the design is embodied and form no part of the claimed design.
